FIG.6

Fig. 7

Fig. 8

FIG. 1 is a perspective view of a combined floodlight and support embodying our design, the view from the opposite side being identical;

FIG. 2 is a perspective view of a second embodiment of our design, the view from the opposite side being identical;

FIG. 3 is a perspective view of a third embodiment of our design;

FIG. 4 is a perspective view of a fourth embodiment of our design;

FIG. 5 is a perspective view of a fifth embodiment of our design;

FIG. 6 is a perspective view of a sixth embodiment of our design;

FIG. 7 is an enlarged side elevation view of the floodlight of each embodiment, the support being omitted for convenience of illustration; and

FIG. 8 is an enlarged top plan view of the floodlight.

The flat surface on the front of each floodlight is a window. The upper ends of the posts shown in broken lines in certain of the figures are for illustrative purposes only and form no part of the claimed design.

This is a division of design application Ser. No. 350,152, filed Apr. 11, 1973.

We claim:

The ornamental design for a combined floodlight and support, substantially as shown and described.
